100,402

DESIGN FOR A BASKET

Nicholas W. Wagner, New York, N. Y.

Application April 22, 1936, Serial No. 62,244

Term of patent 14 years

To all whom it may concern:

Be it known that I, Nicholas W. Wagner, a citizen of the United States, residing at the city of New York, county of Queens, and State of New York, have invented a new, original, and ornamental Design for a Basket, of which the following is a specification, reference being had to the accompanying drawing forming a part thereof.

Fig. 1 is a plan view of a basket embodying my new design, only a portion of the appearance of the bottom of the basket being completed, it being

understood that the remaining portion involves a repetition of the completed section.

Fig. 2 is a fragmentary side elevation of the same. The proportions of the basket shown in Fig. 1 are substantially indicated in this fragmentary view.

I claim:

The ornamental design for a basket substantially as shown and described.

NICHOLAS W. WAGNER.
